Patented Nov. 2, 1926.

UNITED STATES PATENT OFFICE.

JOHN MORTKA, OF POUGHKEEPSIE, NEW YORK.

FOUNTAIN TOOTHBRUSH CONNECTION.

Application filed May 26, 1924. Serial No. 715,832.

This invention relates generally to brushes, being intended more particularly for embodiment in toothbrushes the invention having more particular reference to a 5 novel means whereby the brush may be connected to a water faucet to receive water from the latter while the brush is in use.

The invention has for an object the provision of a simple and novel arrangement 10 comprising a brush having a liquid passage therein which is adapted to be detachably connected by a flexible length of tubing with the faucet.

For further comprehension of the invention, and of the objects and advantages thereof, reference will be had to the following description and accompanying drawing, and to the appended claims in which the various novel features of the invention are 20 more particularly set forth.

Fig. 1 of the drawing is a view showing my improved brush connected to a faucet, the connecting means being shown in elevation and the brush in longitudinal section.

25 Fig. 2 is an end view thereof.

Fig. 3 is a fragmentary sectional view showing the means for engaging the end of the flexible tube with the end of the faucet spout, this view being taken on the line 30 3—3 of Fig. 2.

Fig. 4 is a side view showing a modified means for clamping the head on the end of the flexible tube to the faucet.

In the drawing the reference numeral 10 35 indicates the body of an ordinary faucet which is shown as formed on one end with a screw threaded nipple 11 for connection to a supply pipe or tank, the other end of the faucet being projected in the form of 40 the usual spout 12. The usual valve handle is shown at 13. A toothbrush which is in the main of ordinary construction is shown in Fig. 1 of the drawing as connected to the faucet by a flexible length of tubing 15. 45 This tube 15 connects at one end to the end of the handle portion 16 of the brush, a fluid passage 17 leading through this handle to the backing portion 18 of the brush where it may communicate with the 50 ends of longitudinal grooves such as 19 in the said backing, the water being conducted through this tube and the grooves 19 outward between the bristles 21 of the brush.

55 The outer end of the tube 15 extends upward through a short sleeve 25 the bore whereof is outwardly flared at its upper end

as at 26. The tube is secured in this sleeve by means of a tapered tip or projection 27 from the underside of the cap 28 which is screwed upon the exteriorly threaded upper 60 end of the sleeve. This tip 27 engages in the upper end of the tube 15 and forces the latter against the flaring top 26 of the sleeve bore. A passage 30 for the water leads upward through the tip 27 and cap 28. The sleeve 25 is enlarged and exteriorly screw-threaded at its lower portion as at 32 and above this lower portion it is surrounded by a washer 33 which is adapted to bear on the 65 end of the spout. Screwed on the lower end of the sleeve 25 is a flat ring 34 which forms an abutment for the washer. The parts just referred to may be said to constitute a head to which the tube 15 is connected.

70 For connecting the parts just described to the spout of the faucet I provide a pair of straps 37 which are pivotally attached at one end as at 28 to the opposite sides of the ring 34 and which extend obliquely upward on opposite sides of the body of the faucet. 75 One of these straps is formed on its upper end with an aperture 38 in which engages the diminished end 39' of a cross 39 which is 80 pivoted to the other strap, this cross bar extending behind the upwardly extending part 10' of the faucet body 10. Threaded 85 through the cross bar 39 is a set screw 42 which is provided with a suitable head 43 and which is adapted to bear on the rear of the faucet part 10' to clamp the washer 33 against the mouth of the faucet spout 12. 90 In order to cause the ends of the straps 37 which connect to the ring 34 to be given an upward movement when the screw 42 is 95 tightened I may hinge to a cross piece 45 connecting the straps, a short distance from the said end, a bail 46 which straddles the spout and which extends at an oblique angle with respect to the straps, so that when the screw 42 is tightened the tendency of the 100 parts 37 and 46 to straighten out with respect to one another causes an upward swinging movement of the forward lower ends of the straps.

105 It is believed that the manner of operation and use of my improved device will be readily understood from the above description. To apply the same to the faucet the straps 37 are passed upward on opposite sides of the faucet body until the washer 33 abuts against the mouth of the spout 12, the bail 46 being slipped over the spout. The 110

cross bar 39 is then swung on its pivot to engage the other strap, the straps being sprung outwardly slightly to permit of the tip 39' engaging in the aperture 38. The screw 42 is then tightened.

In Fig. 4 of the drawing I have shown a modified arrangement in which a forked lever 50 has its forked end pivotally connected with the ring 34 and has pivotally connected thereto, between the ends thereof, a bail 51 somewhat longer than the bail 46, which engages over the top of the spout. Through the other end of the lever a set screw 52 is threaded and is adapted to bear upward on the body 10. The parts are otherwise as above set forth.

Having thus described my invention, what I claim as new and desire to protect by Letters Patent of the United States is as follows:

1. In a device of the class described, a flexible pipe provided at one end with an outwardly tapered tip engaging the outwardly flared upper end portion of a bore in a sleeve having male threads on upper and lower ends, the male threads on upper end threadedly engaging a cap having a center aperture and pressing the tip of said pipe into engagement with the bore of said sleeve, the male threads on the lower end threadedly engaging a ring abutting a washer on the middle section of said sleeve, said ring having pivotally attached straps extendable along opposite sides of said faucet, one of said straps having pivoted thereto a cross piece engageable in an aperture in other of said straps, said cross piece being centrally provided with a set screw capable of abutting against said faucet, and said straps having pivotally mounted thereon at a point along their length a cross piece carrying a bail capable of straddling the spout of said faucet.
2. In a device of the class described, in means for securing a tube to a faucet, the

combination of a sleeve having male threads on upper and lower ends and a central bore outwardly flared at the upper end engageable with the outwardly tapered tip of said tube, a cap having a central aperture 50 screwed on upper end of said sleeve, a ring screwed on the lower end of said sleeve, a washer on the middle section of said sleeve abutable against end of spout of said faucet, straps pivotally attached to said ring extending on opposite sides of said faucet, a cross piece pivoted to end of one of said straps engageable in an aperture in other of said straps, a set screw operative in said cross piece adapted to abut said faucet, a 60 cross piece pivotally held in said straps at a point along the length of said straps, a bail engaging latter cross piece adapted to straddle said faucet.

3. In a device of the class described, in means for securing a tube to a faucet, the combination of a sleeve having male threads on upper and lower ends and a central bore outwardly flared at the upper end engageable with the outwardly tapered tip of said tube, a cap having a central aperture 65 screwed on upper end of said sleeve adapted to engage tip of tube in flared portion of sleeve, a ring screwed on the lower end of said sleeve, a washer on the middle section 70 of said sleeve abutable against end of spout of said faucet, straps pivotally attached to said ring extending on opposite sides of said faucet, a cross piece pivoted to end of one of said straps engageable in an aperture in other of said straps, a set screw operative in said cross piece adapted to abut said faucet, a cross piece pivotally held in said straps at a point along the length of said straps, a bail engaging latter cross piece adapted to straddle said faucet.

In testimony whereof I have affixed my signature.

JOHN MORTKA.
